CLAIM

The ornamental design for a bundle body, as shown and described.

DESCRIPTION

FIG. 1 is a front, top perspective view of a bundle body showing the new design;

FIG. 2 is a rear, bottom perspective view thereof;

FIG. 3 is a front elevation view thereof, the rear elevation view being identical thereto;

FIG. 4 is a left side elevation view thereof, the right side elevation view being identical thereto;

FIG. 5 is a top plan view thereof; and,

FIG. 6 is a bottom plan view thereof.

The broken lines shown in the drawings illustrate portions of the bundle body that form no part of the claimed design.
